UNITED STATES PATENT OFFICE.

GEORGE C. HALL, OF SPRINGFIELD, OHIO, ASSIGNOR TO THE ENTERPRISE COMPANY, OF SAME PLACE.

DESIGN FOR AN ADVERTISING-STAND.

SPECIFICATION forming part of Design No. 25,011, dated December 24, 1895.

Application filed February 5, 1895. Serial No. 537,420. Term of patent 3½ years.

To all whom it may concern:

Be it known that I, GEORGE C. HALL, a citizen of the United States, residing at Springfield, in the county of Clark and State of Ohio, have invented a certain new and useful Design for an Advertising-Stand, of which the following is a specification, reference being had therein to the accompanying drawing.

This invention relates to a new and original design for an advertising-stand.

In the accompanying drawing, on which like reference-letters indicate corresponding parts, the figure is a perspective view of my design.

The leading feature of my design consists in a diamond-shaped plaque, upon the front of which is the representation, in relief, of a human face holding a toy in its mouth and with the cheeks puffed out as in blowing.

A base is shown at A, carrying an upright standard B and a branch C. A diamond-shaped plaque D surmounts the standard, and on the surface of the plaque is the representation E of a human face, in relief, with an intended homely countenance having the expression of blowing, the cheeks being puffed out. A toy F is in the mouth.

Having thus fully described my design, what I claim is—

The design for an advertising stand herein shown and described.

In testimony whereof I affix my signature in presence of two witnesses.

GEORGE C. HALL.
